L. H. GANO, OF NEW YORK, N. Y.

Letters Patent No. 83,704, dated November 3, 1868.

IMPROVEMENT IN HAND-STAMPS.

The Schedule referred to in these Letters Patent and making part of the same.

To all whom it may concern:

Be it known that I, L. H. GANO, of New York, in the State of New York, have invented a new and useful Improvement in Automatic Postal and Cancelling Fountain-Stamps; and I do hereby declare that the following is a full, clear, and exact description of the same, reference being had to the accompanying drawings, and letters of reference marked thereon, making a part of this specification, in which—

Figure 1 is a longitudinal central section through the standards *a a*.

Figure 2 is a side elevation, showing the ratchet-cam and spring-dog.

Figure 3 is a side elevation of the stem-valve *d*.

To enable those skilled in the art to make and use my invention, I now proceed to describe its construction and operation.

Similar letters in the drawings refer to like parts.

This invention consists of a hand-stamp, for use in post or other offices, the main features of which are a self-inking apparatus, and a revolving and reciprocating die, with four or more faces, each of which comes successively in contact with the inking-pad, and at the second or other partial revolution thereafter, comes in contact with the surface to be impressed, by the use of which apparatus but one motion is required in order to perform both the inking and stamping-operations, as will hereinafter more fully appear.

A represents the handle of a hand-stamp, the same being hollow. Within the cavity is placed an ink-receptacle, *b*, provided with a screw-cap at its upper end, and terminating in a nipple, *b'*, with a conical cavity, said nipple projecting beyond the bottom of the handle *A*, and entering a suitable cavity in the upper side of the pad-holder *c*. The lower part of the receptacle *b* is solid, with the exception of a conical passage; *b''*, a continuation of the cavity within the nipple *b'*.

Within the receptacle *b* is a stem-valve, *d*, the lower end of which is made to fit the conical passage *b''*, so as to close the same tightly. A smaller stem, *d'*, is attached to the nether extremity of the stem *d*, projecting beyond the orifice of the nipple *b'*, and through a central cavity in the pad-holder *c*, and also through a small perforation, *c''*, in the centre of the pad *c*, the end of the smaller stem *d'* being about flush with the surface of the pad.

A spiral spring, *e*, surrounds the upper portion of the stem, being confined between a flange, *d''*, of the stem and the cap of the ink-fountain. It is obvious that when the valve-stem *d* is raised from the seat *b'*, if there be any ink in the fountain, it will flow through the nipple *b'*, and along the stem *d'*, from which it will be communicated to the pad *c*.

The pad-holder *c* is merely a metal disk with a flange around its edge, within which is placed the pad *c*. Cam-ears *c'' c''* project from opposite sides of the pad-holder, which enter recesses *a' a'*, in the standards *a*,

by means of which, and the set-screw *a''*, and also the nipple *b*, entering its central cavity, the pad-holder is kept in place, whence it may be removed at pleasure.

The standards *a* are hollow, and within them are placed slotted arms *h h*, through the slots of which pass pins *h'*. Between the ends of the arms *h*, and the bottoms of the orifices in the standards, are spiral springs *h''*, the pins *h'* and slots being for the purpose of preventing the arms *h* from being ejected from the standards *a*, by the action of these springs.

In suitable bearings in the arms *h* are placed the journals of the revolving die *B*, provided with four or more stamping-faces. When one of these faces is impressed upon any surface, with the usual impact, the springs *h''* in the hollow standards *a* yield sufficiently to allow the said standards to slide down upon the arms *h*, which motion brings the lower end of the stem *d* against the upper face of the die. Said stem is thereby lifted, and a flow of ink follows, as before described. The inking-pad *c* is brought in contact with the upper face of the die at the same time as the stem *d*, and the face thereby inked. By the same downward motion of the standards *h*, the spring-pawl *i* is thrust over one of the teeth *k'* of the ratchet *k*, rigidly attached to one end of the die *B*.

When the instrument is raised to strike another blow, the springs *h''* are extended, and, by means of the pawl *i* and ratchet *k*, the die is turned a quarter revolution, which brings another one of the faces, suitably inked, underneath, and subjects another to the action of the pad above.

Hence, it appears that the inking and stamping-motions of this instrument are one and the same. This, however, I do not claim as new, but having thus fully described my invention,

What I claim as new, and desire to secure by Letters Patent, is—

1. The combination of the revolving stamp-head *B* with inking-pad *c* and ratchet *k*, substantially as and for the purpose set forth.

2. Disclaiming the use of an inking-ribbon in a postal and cancelling-stamp, an apparatus for automatically inking the die, substantially as described.

3. The conical stem-valve *d*, provided with the spiral spring *e*, when said stem is applied to the fountain of a self-inking stamp, and used in combination with the perforated pad *c*, as and for the purpose set forth.

4. The standards *a*, in combination with arms *h* and springs *h''*, in the manner and for the purpose described.

5. The pad-holder *c*, provided with the cam-ears *c'' c''*, in combination with recessed standards *a* and thumb-screw *a''*, in the manner and for the purpose described.

L. H. GANO.
